(57) **CLAIM**

The ornamental design for a folding box, as shown and described.

DESCRIPTION

FIG. 1 is a front, top perspective view of a first embodiment of a folding box, showing my new design;
FIG. 2 is a rear, bottom perspective view thereof;
FIG. 3 is a front elevation view thereof;
FIG. 4 is a rear elevation view thereof;
FIG. 5 is a left side elevation view thereof;
FIG. 6 is a right side elevation view thereof;
FIG. 7 is a top plan view thereof;
FIG. 8 is a bottom plan view thereof;
FIG. 9 is another perspective view of the folding box, shown in an unfolded configuration;
FIG. 10 is a front, top perspective view of a second embodiment of the folding box;
FIG. 11 is a rear, bottom perspective view thereof;
FIG. 12 is a front elevation view thereof;
FIG. 13 is a rear elevation view thereof;
FIG. 14 is a left side elevation view thereof;
FIG. 15 is a right side elevation view thereof;
FIG. 16 is a top plan view thereof;
FIG. 17 is a bottom plan view thereof; and,
FIG. 18 is another perspective view of the folding box, shown in an unfolded configuration.
